ROLLING MILLWORK MEASURING

Rolland E. Peterson, Aetna, Ind., assignor to
 American Sheet and Tin Plate Company, a
 corporation of New Jersey

Application September 21, 1933, Serial No. 690,467

4 Claims. (Cl. 80—47)

This invention is a device intended for use with a rolling mill to measure the work so that the roller may properly regulate his pressures and number his passes to produce desired lengths. It is particularly intended to be used with a sheet or tin plate mill provided with an automatic catcher table.

Referring to the drawings:

Figure 1 is a diagrammatic side elevation of an example of the invention used with a hot mill.

Figure 2 is a top plan of Figure 1.

Figure 3 is an enlarged side elevation of a detail in Figure 1.

Figure 4 is a cross-section from the line IV—IV in Figure 3.

Figure 5 is an enlarged side elevation of another detail from Figure 1.

Figure 6 is a cross-section from the line VI—VI in Figure 3.

A stand of hot rolls 1 is provided with roller and catcher tables 2 and 3. These tables are the type which automatically pass sheet packs through the pass of the stand and return them over the top roll.

In the present instance pinch-rolls 4 and 5 are carried by the catcher table 3 and receive the work coming from the roll stand 1. These pinch-rolls comprise coacting double disks and are driven at the same speed that the catcher table carries the work. This may conveniently be accomplished by fixing the lower roll 5 to the sprocket shaft of the catcher table. It is assumed that this table includes endless carrying chains mounted and driven by sprockets whose rotative directions are reversed during the return of the work.

The upper pinch-roll 4 is mounted on the catcher table by a bracket 6 pivotally carried by a pair of upstanding arms 7. This bracket 6 also mounts a frame 7a carrying mechanism driven by the upper pinch-roll 4 for converting the latter's revolutions into linear measurements.

This mechanism includes a shaft 8 connected to the upper pinch-roll 4 by sprockets 9 and 10 and chain 11. The sprocket 9 is loosely mounted on the shaft 8 and the drive is effected by the mutual contact of pins 12 and 13, the former projecting from this sprocket and the latter from an arm 14 fixed to the shaft 8.

The shaft 8 carries a pinion 15 meshed with a gear 16 mounted for free rotation on a shaft 17. This shaft carries a brake drum 18 driven

by the gear 16 through a friction clutch 19. The drum 18 is fixed to the shaft 17 to drive it.

A brake shoe 20 is carried by a toggle-arm 21 and constantly urged into contact with the brake drum 18 by a spring 22. This toggle-arm is constructed to hold the shoe 20 against the drum 18 so that the latter is locked from rotation in an anti-clockwise direction but can rotate in a clockwise direction. When the pinch-roll 4 turns in a work receiving direction the drum 18 is urged in an anti-clockwise direction. The shoe 20 prevents this while the friction clutch 19 allows slippage. When work is discharged from the catcher table the pinch-roll 4 drives the drum 18 in a clockwise direction, which is possible because the shoe 20 will be released by the action of the toggle-arm 21.

A bell-crank 23 raises the toggle-arm 21 to release the shoe 20. The short arm of this bell-crank contacts the under side of the toggle-arm 21 so that the latter is free to rise when urged to do so by the clockwise rotation of the drum 18.

The bell-crank 23 is operated through a connecting-rod 24 by a trigger 25. This trigger is located in the pass of the pinch-rolls 4 and 5 for operation by the passage of work. When work is being received by the catcher it throws the toggle-arm 21 to brake-disengaging position so that the drum 18 is driven by the upper pinch-roll 4. This trigger rides on top of the work during its passage and drops when its end is reached. This immediately permits reapplication of the shoe 20 to the drum 18 so that the revolutions of the latter are stopped. A compression spring 25a may be applied to the rod 24 so that the trigger is normally urged to work-engaging position.

The shaft 17 which turns with the drum 18 may be connected directly to a pointer and dial calibrated in suitable linear units. As this shaft is driven by the pinch-roll 4 only during the actual contact of work, this pointer will read accurately.

Because the driving pinch-roll 4 is constantly rotating at the theoretical speed of the work coming from the hot rolls, due to its being frictionally driven by contact with the pinch-roll 5 which is itself driven by the catcher, there is little danger of a slippage error. The only parts which must be started from a stationary position are the drum 18, shaft 17 and pointer of the dial, these all being relatively light so that their inertia is easily overcome without undue slippage of the clutch 19. The shaft 17 will not be rotated by the pinch-roll 4 until a sheet

operates the trigger 25 so as to release the brake shoe 20 from the drum 18. Therefore, no error is caused by reason of the constant rotation of the pinch-roll 4.

5 The drawings show a telemetric transmitter element 26 arranged in circuit with receiver element 27 which operates a pointer 28 over a dial 29. These telemetric transmitting and receiving elements may be of the Selsyn type, or any other 10 suiting the designer's fancy. This telemetric system is illustrated instead of a pointer directly mounted on the shaft 17 because of the difficulty the mill operator will ordinarily have in 15 obtaining a reading if the indicating instrument is on the catcher's side of the mill.

The various elements described are reset to 20 bring the pointer 28 to zero position by the return of the work through the pinch-rolls 4 and 5 to the roller table. During this movement the 25 trigger 25 is oppositely moved. This is possible because the crank's short arm may freely leave the toggle-arm 21. Reverse rotation of the drum 18 is also possible because of the toggle action of the brake 20.

25 Pins 30, 31 and 32 are carried by the frame 7 to extend towards the drum brake 18. The pin 30 slides in the frame 7 and may be withdrawn by a knob 30^a. It is preferably held in projecting and withdrawn positions by a spring urged plunger 30^b which projects into suitably positioned notches in the pin. These pins are spaced apart.

30 The drum 18 carries a pin 33 which extends 35 towards the frame 7. The pins 30 and 33 are positioned at the same radial distance while the pin 31 is positioned at a greater radial distance. A freely revoluble radial finger 34 encircles the shaft 17 and is of a sufficient length to engage the pins 31 and 32.

40 When the pointer of the indicating instrument is at zero the pins 32 and 33 clasp the finger between them so that clockwise rotation of the drum 18 is positively prevented. When work passes onto the catcher table between the pinch-rolls the drum 18 may revolve in an anti-clockwise direction until its carried pin 33 strikes the pin 30. When the work leaves the catcher the drum 18 will revolve in a clockwise direction until the pin 33 brings the finger 34 against the shaft pin 32.

45 In case of long work the pin 30 is withdrawn by means of its knob 30^a. This permits the pin 33 carried by the drum 18 to pass this withdrawn pin, contact the opposite side of the finger 34 and bring the latter into engagement with the pin 31. Dial resetting motion of the drum 18 then results in movement of the pin 33 back until it strikes the opposite face of the finger 34 and brings it against the pin 32.

50 The time required to return the pins 12 and 13, and the pin 33 provides ample time for the mill operator to observe the reading of the indicating instrument. It is, of course, impossible for the latter to leave its reading position until 55 all the coacting pins interengage.

The shaft 17 may carry a pair of interconnected contacts 35 which cooperate with adjustable contactor segments 36. These segments 36 may be arranged in circuit with the drive of the catcher table so that the latter is not reversed when the circuit is closed by the interconnected contacts 35.

55 More specifically, this arrangement may be effected by mounting the interconnected contacts 35 on an insulating arm 37 fixed to ro-

tate with the shaft 17. The contactor segments 36 might be mounted on an insulating disk 38 rotatably carried by the frame 7 and operable by a knob 39 having a pointer 40 which reads on a dial 41. Then by setting the pointer 40 so that the segments 36 will not be closed by the contacts 35 until the shaft 17 has been rotated to a position causing the indicating instrument to read the desired length, it is possible to effect automatic discharge of the work from the catcher table when this desired length is attained.

10 A summary of the operation involved is as follows:

The pinch-roll 5 is rotated by the catcher's reversing driving mechanism at substantially the theoretical speed of work coming from the mill and in a receiving direction. Since the pinch-roll 4 is in frictional contact with the pinch-roll 5, it is also rotated at this theoretical speed and in a receiving direction. The shoe 20 at this time prevents rotation of the shaft 17, due to its engagement with the drum 18.

15 As soon as work reaches the two pinch-rolls it trips the trigger 25 and so releases the shoe 20 from the drum 18. Simultaneously it takes 20 up the job of rotating the already rotating pinch-roll 4, the drive from the pinch-roll 5 being interrupted by the interposed work 4. The shaft 17 is now rotated by this latter pinch-roll and the trigger is riding the top of the work. As 25 soon as the work leaves the pinch-rolls the trigger falls and permits reapplication of the shoe 20 to the drum 18 so that rotation of the shaft 17 is immediately halted. It follows that the extent of the rotation of the shaft 17 can be 30 utilized to determine the length of the work passed by the pinch-rolls, as has previously been described.

35 As the catcher reverses to return the work over the mill the shaft 17 is reversely driven 40 by the pinch-roll 4 contacting the pinch-roll 5, and this resets the length indicating pointer. This is delayed until the various pins oppositely reengage, this giving the roller time to see the pointer's reading. As soon as the catcher again 45 starts to operate in its receiving direction, the pinch-roll 5 again starts to rotate the pinch-roll 4 which causes the pins to reengage in their initial manner, and the apparatus is again ready to measure the work.

50 Although a specific form of this invention is shown and described in accordance with the patent statutes, it is not intended that its scope be limited thereto, except as defined by the following claims.

I claim:

1. The combination of a roll stand, an elevating catcher table with reversibly operating conveyer means, constantly rotating pinch-rolls mounted at one end of said catcher table adjacent said roll stand, said pinch-rolls rotating in unison with and in the same direction as said conveyer means and means for remotely recording the rotation of pinch-rolls in one direction only.

2. Apparatus for measuring the length of moving work, including the combination of a revolvable element arranged for contact by said work, means for revolving said element at approximately the theoretical speed of said work prior to its being contacted by said work and measuring means responsive to the extent said element is revolved while it is being contacted by said work.

3. Apparatus for measuring the length of

75

- moving work, including the combination of a revoluble element arranged for contact by said work, a source of rotary power, means for connecting said source to revolve said element prior to its being contacted by said work and for disconnecting it from said source when it is contacted by said work, and measuring means responsive to the extent said element is revolved by its being contacted by said work.
- 10 4. The combination of a stand of hot rolls, an automatic reversing catcher for said stand, pinch-rolls carried by said catcher so as to engage work handled by the latter, one of said pinch-rolls being rotatively driven by said catcher and the other being urged into frictional en-
- gagement with the former, a rotative shaft, a friction drive for rotatively connecting said shaft to said other of said pinch-rolls, a brake constructed to normally hold said shaft stationary when said other of said pinch-rolls is revolving in a work-receiving direction, a work-operable trigger arranged between said pinch-rolls and associated with said brake so as to release the latter while work is passing between said pinch-rolls, and length indicating means arranged in 10 driven connection with said shaft, the last named means being constructed for resetting by reverse rotation of said shaft.

ROLLAND E. PETERSON. 15
